UNITED STATES PATENT OFFICE.

JOHN R. ROCHELLE, OF GONZALES, TEXAS.

VEHICLE-AXLE LUBRICATOR.

SPECIFICATION forming part of Letters Patent No. 236,958, dated January 25, 1881.

Application filed June 26, 1880. (No model.)

To all whom it may concern:

Be it known that I, JOHN R. ROCHELLE, of Gonzales, in the county of Gonzales and State of Texas, have invented certain new and useful Improvements in Axle-Lubricators; and I do hereby declare that the following is a full, clear, and exact description of the invention, which will enable others skilled in the art to which it appertains to make and use the same, reference being had to the accompanying drawings, which form a part of this specification.

This invention relates to axle-lubricators; and it consists in the improvements in the construction of the same, hereinafter fully described, and particularly pointed out in the claims.

In the accompanying drawings, Figure 1 is a view, in perspective, of an axle-lubricator embodying the improvements in my invention. Fig. 2 is a vertical longitudinal sectional view, and Fig. 3 is an end elevation.

Referring by letter to the drawings, A designates a semi-tube-shaped arm, which fits upon the axle and is secured thereto by the ordinary band or clip. A sand-band, B, is formed with or secured to the arm A, and when in place is covered by the hub-band.

C designates the oil-cup, provided with a screw-cap, D.

E designates a tube leading from the bottom of the oil-cup, to conduct the oil to the spindle, and said tube E is passed through a

hole or groove drilled or cut in the shoulder-band or collar of the axle.

The oil-cup C has a screw-connection, F, at its base, in order that it may be removed at any time when it may become necessary for the purpose of cleaning the tube E, which may be accomplished by passing a wire through the tube. The tube is incased in a hose, G, of textile fabric, which feeds the oil gradually from the end of the tube to the spindle.

From the foregoing description the operation of the device will be readily understood.

Having thus fully described my invention, what I claim, and desire to secure by Letters Patent, is—

1. In an axle-lubricator, the combination of the arm A, sand-band B, and oil-cup C, provided with the tube E, constructed and operating substantially as set forth.

2. In an axle-lubricator, the combination, with a sand-band having arm A, provided with tube E and screw-connection F, of an oil-cup adjusted in said screw-connection, as set forth.

In testimony that I claim the foregoing as my own I have hereto affixed my signature in presence of two witnesses.

JOHN RUGELEY ROCHELLE.
